UNITED STATES PATENT OFFICE.

JOSEPH LINDBURG, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,169,330.

Specification of Letters Patent. Patented Jan. 25, 1916.

Application filed August 31, 1914. Serial No. 859,314.

To all whom it may concern:

Be it known that I, JOSEPH LINDBURG, a citizen of the United States, residing in New York city, in the county of New York and State of New York, have invented certain new and useful Improvements in Type-Writing Machines, of which the following is a specification.

This invention relates to typewriting machines, and has particular reference to means whereby labels or other relatively small work-pieces may be removably connected to a revoluble platen to be line-spaced thereby.

15 The invention is applicable in those cases where the work-piece on account of its small size, is incapable of support upon the platen and of feeding thereover by aid of the usual feed rolls; the improvement consisting of 20 means disposed at one end of the platen to clamp the work-piece upon the platen surface to revolve with the platen; the clamping means being of such character that they may pass the feed rolls, if necessary. The 25 clamping means, however, which are operated by a pivotal lever, having intermediate connections whereby said clamping means may be released from the platen surface, are engaged by said lever with the 30 platen frame or carriage to be thereby held at rest while the platen is rotated in the ordinary operation of the machine with work-sheets of a size operable with the usual feed rolls.

35 This invention comprises a work-piece clamp which can be rendered operative or inoperative by the movement in opposite directions of a lever, and which when not in use, is non-interfering with the usual operation of the machine.

40 When the invention is applied to a typewriting machine of usual construction, the platen is shortened at one end to provide space for the introduction of the necessary mechanism between the platen end and the platen frame. Where shortened, the platen has an extending hub carrying an annular, beveled disk; a clamping plate, which lies upon the platen surface, having 45 depending members to frictionally engage said disk; and a lever pivoted upon a sleeve or member supported by said hub, said lever serving when operated in one direction to draw the plate into clamping relation 50 with the platen surface in any rotative posi-

tion of the platen relative to said plate, and to frictionally connect its depending portions with said disk, whereby the platen and clamping plate will rotate together; and detaining means upon the platen frame for 60 said lever when rocked in the opposite direction to release the clamping plate, whereby said clamping plate will be held stationary while the platen is rotated freely in the performance of its usual work.

65 One of the members depending from the clamping plate is bifurcated to form legs which straddle the aforesaid hub, said legs at their lower ends being pivotally connected with the shank of a yoke-like link, whose opposite arms are respectively pivotally connected with the arms of a bell-crank, which is fulcrumed to the hub; said bell-crank comprising the operating lever before referred to, and being preferably bifurcated for pivotal connection at opposite sides of the hub, its bifurcate members uniting to form an operating finger piece.

70 A light spring presses the operating lever normally between retaining fingers or other engaging means rigidly mounted upon the machine to normally hold the operating lever at rest with the clamping plate released from the platen.

75 Other features and advantages will hereinafter appear.

80 In the accompanying drawings—Figure 1 is a perspective front elevation of a platen, showing the label or other work-piece clamping plate and the operating means therefor. Fig. 2 is a partial detail view, showing the platen end, and, in vertical section, showing the hub with the flange and sleeve thereon, also the casing therefor. Fig. 3 is a similar view, the hub and sleeve 85 being herein shown in full lines, with the operating lever and the clamp as released from the platen. Fig. 4 is an end view, partly in section, through the line 4—4 of Fig. 3. Fig. 5 is a similar view to that of Fig. 3, showing the clamp in operation. Fig. 6 is a perspective detail of the clamp, with its supporting and frictional binding members. Fig. 7 is a detail of the operating lever. Fig. 8 is a detail of the connecting link between the operating lever and the clamp support.

85 In the example of my invention illustrated herein, wherein it is shown applied to an Underwood typewriting machine, 1 in-

dicates the platen, with the platen axle 2 supported by the platen frame 3 having the usual cover plates 4.

The clamping mechanism which is the 5 subject of this application, is here shown as applied at the right-hand end of the platen, the usual line-spacing wheel 5 with its operating mechanism being at the left-hand end.

10 In order to provide space between the platen end and the platen frame to apply my improvement, the platen is shortened at the right-hand end to leave sufficient clearance, the length of the platen being filled out 15 through the clearance by an elongated hub 6, which carries an annularly disposed disk or flange 7, whose outer surface is beveled as at 8, to form a wedge.

The clamping means whereby a label or 20 other work-piece may be connected to the platen surface, comprises a stiff strip or plate, as 9, extending longitudinally over a sufficient portion of the platen surface to serve the desired purpose; said strip being 25 preferably curved transversely to enable it to conform to the platen contour, and having relatively flexible fingers 10, which may extend from a separate strip surmounted and held by strip 9. The flexible fingers 10 are 30 intended for the purpose of gripping the work-piece securely without marring its surface.

The plate or clamp 9 is carried by a supporting member 11, to which it is secured 35 as by screws 12, said member 11 depending at right angles from said plate 9, and being bifurcated to form legs 13, which straddle the hub 6, said member 11 with its legs 13 lying between the disk 7 and the platen end, 40 which may have an end plate 14. The outer end 15 of the plate 9 is bent at right angles thereto to form an overhanging arm parallel with and spaced from the member 11, that the flange 7 may enter between said 45 member 11 and arm 15 to be wedged therein by the beveled surface of flange 7 bearing against the inner surface of arm 15, thus frictionally holding the plate 9 seated in clamping position upon the platen. The 50 end of arm 15 is curved along its edge, as at 16, that it may lie over the curved surface of the hub 6, and thereby extend the available surface of said arm for frictional engaging contact with flange 7.

55 The supporting member 11 is operable by means of a bell-crank having separated arms 17 in the form of a yoke, straddling a sleeve or support 18 loose upon hub 6, and pivoted to said sleeve as at 19; said arms 17 60 merging at their outer ends into a finger piece 20, by which said bell-crank may be manipulated; and the arms 17 at the opposite sides of their pivots, respectively pivotally engaging the yoke-like arms 21 of a link whose shank portion 22 is pivotally

supported transversely between the legs 13 of the member 11, as at 23.

By reason of the lever and link connection aforesaid with the support for the clamping plate 9, the latter will be moved 70 toward the platen surface to clamp a work-piece thereon, by movement of the finger piece toward the platen end; while movement of the finger piece in the opposite direction will move the plate 9 away from 75 the platen surface, to release a work-piece therefrom, or for the purpose of introducing a workpiece under said plate.

It should be noted that the plate 9 moves to and from the platen surface in parallelism therewith, due to the fact that its right angular supporting member 11, being guided between the end plate 14 and flange 7, is thereby directed in a plane perpendicular to the platen axis. In this manner the clamping plate or member 9 by reason of radial movement toward and from the platen, is assured of always seating evenly upon the platen surface portion toward which it is directed, and of thereby uniformly gripping 80 the entire interposed portion of the work-piece to be held thereby.

The operating members just described as disposed at the platen end, may be inclosed within a housing or cap, as 24, which may 85 be connected to or integral with the sleeve 18, said cap or housing with said sleeve thus being loosely mounted upon the hub 6. The inwardly directed end of the sleeve 18 may 90 abut against a collar 25 that is fast upon 103 said hub, and serves as an end bearing to prevent undue frictional contact between the peripheral edge of cap 24 and the end plate 14 when the platen is rotating independently of the clamping plate 9. The 105 housing or cap 24 has a longitudinal slot 26 in its wall to receive and permit the operation of the finger piece 20, said slot being enlarged at its outer portion, as at 27, to 110 accommodate the support 11, and to thereby 115 connect the cap and sleeve with said support and the clamping plate, that these members may move in unison, whether the plate 9 be fast upon the platen or released therefrom.

It having been noted that the finger piece 115 20, when moved in the direction of the platen end, has thereby operated the clamping plate mechanism to draw said clamping plate into close contact with the platen surface and to create the frictional clutch 120 engagement whereby said clamping plate is caused to rotate with the platen in the line-spacing operation of the latter, so, when the finger piece 20 is moved away from the platen end, thereby operating the mechanism aforesaid to release the clamping plate 9 from the platen surface, leaving the platen free to rotate without carrying with it said clamping plate, anchorage means are provided in a fixed position upon the platen 130

frame, as, for example, upon the cover plate thereof, to engage said finger-piece when thus thrown outwardly, whereby said finger piece with the mechanism it controls and the 5 clamping plate, are positively held stationary in conjunction with the sleeve and housing aforesaid while the platen is free to rotate. Said engaging means may consist of the herein-shown fork or fingers 28 extending 10 from a strip 29 that is secured to the cover plate 4, said fork or fingers being arranged to receive the finger-piece 20 as it moves outwardly to the releasing position.

In order that the finger piece 20, when 15 thus moved to the releasing position, may be held against accidental dislodgment therefrom, a light spring 30 is secured at one end to the housing 24, and arranged at its other end to be passed by and then to bear against 20 said finger piece, pressing the latter with sufficient tension for the purpose against its engaging seat.

A collar 31 fast to the platen axle 2, lies 25 against the sleeve 18 or housing 24 indifferently, to confine said sleeve and housing axially between said collar 31 and the collar 25.

Variations may be resorted to within the 30 scope of the invention, and portions of the improvements may be used without others.

Having thus described my invention, I claim:

1. In a typewriting machine having a rotatable platen, a shaft for said platen, a support 25 fixed to rotate on said shaft, and means carried by said support and pivoted astride thereof, for holding the work-piece against said platen.

2. In a typewriting machine having a rotatable platen, a shaft for said platen, a support 40 fixed to rotate on said shaft, and means pivoted upon said support for holding the work-piece against said platen.

3. In a typewriting machine having a rotatable platen, a shaft for said platen, a support 45 rotatably mounted on said shaft, and means including a pivoted lever, and a link carried by said support for holding the work-piece against said platen.

50 4. In a typewriting machine having a rotatable platen, a shaft for said platen, a support rotatably mounted on said shaft, and means including a pivoted yoke lever mounted upon said support, a link connected to said lever, a clamp, and a supporting member for said clamp connected to said link.

55 5. In a typewriting machine, a rotatable platen, a shaft for said platen, a support fixed to rotate on said shaft, means carried 60 by said support for holding a work-piece against said platen, and a device mounted on said platen shaft adapted to be frictionally engaged by said means.

65 6. In a typewriting machine, in combination, a revolute platen, a hub at one end of

said platen, an independently revolute sleeve on said hub, a work piece clamp, and a link and lever connection between said sleeve and clamp to move the latter into and out of effective position.

70

7. In a typewriting machine, in combination, a revolute platen, a hub at one end thereof, an independently revolute sleeve on said hub, a work-piece clamp, connections between said sleeve and clamp to move the latter into and out of clamping relation with the platen and a wedge-surfaced disk between the clamp and the platen to maintain the two in adjusted relation to each other.

75

8. In a typewriting machine, in combination, a revolute platen, a hub at one end thereof, an independently revolute sleeve on said hub, a work-piece clamp, connections between said sleeve and clamp to move the latter into and out of clamping relation with the platen, and frictional means upon the platen shaft to engage said clamp when seated.

80

9. In a typewriting machine, in combination, a revolute platen, a hub at one end thereof, an independently revolute sleeve on said hub, a work-piece clamp, connections between said sleeve and clamp to move the latter into and out of clamping relation with the platen, and a beveled flange on said hub to frictionally engage said clamp with said platen when seated thereon.

95

10. In a typewriting machine, in combination, a revolute platen, a hub at one end thereof, an independently revolute sleeve on said hub, a work-piece clamp, and a lever fulcrumed on said sleeve to move said clamp into and out of clamping relation with said platen.

100

11. In a typewriting machine, in combination, a revolute platen, a hub on one end thereof, an independently revolute sleeve on said hub, a work-piece clamp, a lever fulcrumed on said sleeve to move said clamp into and out of clamping relation with said platen, and a finger-piece to operate said lever.

110

12. In a typewriting machine, in combination, a revolute platen, a hub at one end thereof, an independently revolute sleeve on said hub, a work-piece clamping plate extending over a portion of the platen surface, a support for said plate movable perpendicularly to the platen axis, and a lever fulcrumed on said sleeve to move said clamping plate into and out of clamping relation with said platen.

115

13. In a typewriting machine, in combination, a revolute platen, a hub at one end thereof, an independently revolute sleeve on said hub, a work-piece clamping plate extending over a portion of the platen surface, a support for said plate movable perpendicularly to the platen axis, a lever ful-

125

130

crummed on said sleeve to move said clamping plate into and out of clamping relation with said platen, and a finger piece to operate said lever.

5 14. In a typewriting machine, in combination, a revoluble platen, an elongated hub at one end thereof, an independently revoluble sleeve on said hub, a work-piece clamping plate extending over a portion of the 10 platen surface, a support for said plate movable perpendicularly to the platen axis, a bell crank fulcrumed on said sleeve, and a link between said bell crank and clamping plate support, whereby said clamping plate 15 may be moved into and out of clamping relation with said platen.

15. In a typewriting machine, in combination, a revoluble platen, an elongated hub at one end thereof, an independently revoluble sleeve on said hub, a work-piece clamping plate extending over a portion of the 20 platen surface, a support for said plate movable perpendicularly to the platen axis, a bell crank fulcrumed on said sleeve, a link 25 between said bell crank and clamping plate support, whereby said clamping plate may be moved into and out of clamping relation with said platen, and a finger-piece to operate said bell crank.

30 16. In a typewriting machine, in combination, a rotatable platen, an elongated hub at one end thereof, an independently revoluble sleeve on said hub, a work-piece clamp, operating means therefor, an extension upon 35 said clamp movable therewith and into and out of frictional engagement with said hub, to connect said clamp to said platen when in clamping relation therewith, for rotation in unison, and to disconnect it therefrom 40 when released from clamping relation, to permit relative movement of said platen and clamp.

17. In a typewriting machine, in combination, a revoluble platen, a hub at one end 45 thereof, an independently revoluble sleeve on said hub, a work-piece clamp, connections between said sleeve and clamp to move the latter into and out of clamping relation with the platen, and an extension upon said 50 clamp movable therewith and into and out of frictional engagement with said hub, to connect said clamp to said platen when in clamping relation therewith, for rotation in unison, and to disconnect it therefrom when 55 released from clamping relation, to permit relative movement of said platen and clamp.

18. In a typewriting machine, in combination, a revoluble platen, an elongated hub at one end thereof, an independently revoluble 60 sleeve on said hub, a work-piece clamp, operating means therefor, a beveled flange on said hub, a right angular extension upon said clamp movable therewith and into and out of frictional engagement 65 with said flange, to connect said clamp to

said platen when in clamping relation therewith, for rotation in unison, and to disconnect it therefrom when released from clamping relation, to permit relative movement of said platen and clamp.

70 19. In a typewriting machine, in combination, a revoluble platen, an elongated hub at one end thereof, an independently revoluble sleeve on said hub, a flange on said hub, a work-piece clamping plate extending over a portion of the platen surface, a support for said plate movable perpendicularly to the platen axis, said support being bifurcated to straddle said hub and being guided between said flanges and the platen end, a 75 bell crank fulcrumed on said sleeve, and a link between said bell crank and clamping plate support, whereby said clamping plate may be moved into and out of clamping relation with said platen.

80 20. In a typewriting machine, in combination, a revoluble platen, an elongated hub at one end thereof, an independently revoluble sleeve on said hub, a flange on said hub, a work-piece clamping plate extending over a portion of the platen surface, a support for said plate movable perpendicularly to the platen axis, said support being bifurcated to straddle said hub and being guided between said flange and the platen 85 end, a bell crank fulcrumed on said sleeve, a link between said bell crank and clamping plate support, whereby said clamping plate may be moved into and out of clamping relation with said platen, and a finger-piece to 90 operate said bell crank.

21. In a typewriting machine having a revoluble platen, the combination of means, supported rotatably upon the shaft of said platen, a lever pivoted upon said supporting 105 means, a work clamp, and a connection between said lever and work clamp whereby the lever may be made to put the clamp into and to withdraw it from operative position.

22. In a typewriting machine having a 110 revoluble platen, the combination of means, supported independently of said platen, for releasably clamping a work-piece to the platen, a finger-piece for moving said clamping means into and out of operative position, and fixed retaining means to engage said finger-piece when the latter has moved said clamping means to released position.

23. In a typewriting machine, in combination, a revoluble platen, a platen frame, an 115 elongated hub at one end of said platen, an independently revoluble sleeve on said hub, a work-piece clamp, a lever fulcrumed on said sleeve to move said clamp into and out of clamping relation with said platen, a 120 finger-piece to operate said lever, and an anchorage in fixed relation with the platen frame to engage said finger-piece when the latter has moved said clamp out of clamping 125 relation with said platen, to thereby hold 130

- said clamp at rest while the platen is rotated independently thereof.
24. In a typewriting machine, in combination, a revolute platen, a work-piece clamp extending over a portion of the platen surface, said clamp having relatively flexible fingers to press a work-piece to the platen, a sleeve rotatably mounted upon the shaft of said platen, and means pivoted upon said sleeve for applying said clamp to and releasing it from the platen surface.
25. In a typewriting machine, in combination, a revolute platen, a work-piece clamp extending over a portion of the platen surface, a sleeve upon said shaft, and means pivoted upon said sleeve and movable in one direction for simultaneously applying said clamp to the platen surface and connecting it with the platen to rotate therewith, said means also being movable in the opposite direction to simultaneously remove said clamp from the platen surface and disconnect it from the platen, whereby said platen and clamp are separately movable.
26. In a typewriting machine, in combination, a revolute platen, a work-piece clamp extending over a portion of the platen surface, a sleeve upon said shaft, means pivoted upon said sleeve and movable in one direction for simultaneously applying said clamp to the platen surface and connecting it with the platen to rotate therewith, said means also being movable in the opposite direction to simultaneously remove said clamp from the platen surface and disconnect it from the platen, whereby said platen and clamp are separately movable, and a finger-piece to operate said clamp applying and removing means.
27. In a typewriting machine, in combination, a revolute platen, a work-piece clamp extending over a portion of the platen surface, means movable in one direction for simultaneously applying said clamp to the platen surface and connecting it with the platen to rotate therewith, said means also being movable in the opposite direction to simultaneously remove said clamp from the platen surface and disconnect it from the platen, whereby said platen and clamp are separately movable, a finger-piece to operate said clamp applying and removing means, and an anchorage to engage said finger-piece when the latter has moved said clamp to disconnect it from the platen and out of clamping relation with the platen surface, to thereby hold said clamp at rest while the platen is rotated independently thereof.
28. In a typewriting machine having a revolute platen and an axle therefor, the combination of a sleeve mounted free to turn but not to slide upon said axle, a lever pivoted astride said sleeve, a work piece clamp, and connections between said lever and clamp whereby the lever when turned one way draws the clamp against the platen and when turned the other way withdraws the clamp from the platen.
29. In a typewriting machine, in combination; a revolute platen, an elongated hub at one end thereof, an independently revolute sleeve on said hub, separated collars fast upon said hub at opposite ends of said sleeve to prevent longitudinal movement of the latter, a work-piece clamp, and connections between said sleeve and clamp to move the latter into and out of clamping relation with the platen.
30. In a typewriting machine, in combination, a revolute platen, an elongated hub at one end thereof, an independently revolute sleeve on said hub, a work-piece clamp, connections between said sleeve and clamp to move the latter into and out of clamping relation with the platen, a housing carried by said sleeve for said connections, and collars fast upon said hub at opposite ends of said sleeve to prevent longitudinal movement of said sleeve, housing and connections.
31. In a typewriting machine having a revolute platen and an axle therefor, the combination of a sleeve mounted free to turn but not to slide upon said axle, a lever pivoted astride said sleeve, a work piece clamp movable radially toward and from the platen, and connections between said lever and clamp whereby the lever when turned one way draws the clamp radially against the platen and when turned the other way withdraws the clamp radially from the platen.
32. In a typewriting machine having a rotatable platen, a shaft for said platen, a support mounted upon the shaft to turn thereon, a work piece clamp adapted to move radially to and from the platen, and means carried by the support and connected to the work piece clamp for moving the latter radially of the platen toward and from the platen.
33. In a typewriting machine having a rotatable platen, a shaft for said platen, a support mounted upon the shaft to turn thereon, a work piece clamp adapted to move radially to and from the platen, and means pivoted astride of the support and connected to the work piece clamp for moving the latter radially of the platen toward and from the platen.

JOSEPH LINDBURG.
